UNITED STATES PATENT OFFICE.

LOUIS HOLLAND LETZ, OF CHICAGO, ASSIGNOR OF ONE-HALF TO JOHN SCHRUM, OF DOLTON, ILLINOIS.

CORN-PLANTER.

SPECIFICATION forming part of Letters Patent No. 283,621, dated August 21, 1883.

Application filed May 3, 1883. (No model.)

To all whom it may concern:

Be it known that I, LOUIS HOLLAND LETZ, a subject of the Emperor of Germany, residing at Chicago, in the county of Cook and State 5 of Illinois, have invented certain new and useful Improvements in Corn-Planters, of which the following is a specification, reference being had therein to the accompanying drawings.

10 This invention relates to the class of corn-planters that have sled-runners to open the furrows, seed-boxes that drop the corn at proper intervals into such furrows, which are then closed again by wheels passing over the 15 furrows. Such a machine generally consists of two sections, the frames of which are pivotally coupled, the forward section having the rigid pole for hitching the horses, the sled-runners for opening the furrows, and behind 20 these and in line therewith the seed-boxes, while the rear section consists of a two-wheel truck that has a seat for the driver and levers for controlling the operation of the machine.

25 My invention particularly relates to devices for automatically operating the seed-box slides, and for marking the spots for the next adjacent parallel rows to be planted, which devices are attached to the hind truck and 30 driven by the traction of the truck-wheels. I have in the drawings only shown the rear section or truck of the corn-planter, the fore part of the machine being of the usual construction.

35 My invention consists of the novel devices and combinations of devices hereinafter described and specifically claimed.

In the accompanying drawings, Figure 1 represents a plan view of the hind truck of a corn-planter having my attachments. Fig. 2 represents a front elevation of the same. Fig. 3 is an elevation of the crank-disk and vibratable arms. Fig. 4 is a front view of the crank-oscillating mechanism; Fig. 5, an elevation of the fulcrum-bracket for the oscillating crank and vibratable arms. Fig. 6 is an elevation and sectional edge view of the friction-coupling. Fig. 7 represents a rear elevation of the coupling lever and sleeve; Fig. 8, a sectional elevation of one set of corn-marker arms, and 45 Fig. 9 an end elevation of one of the V-brackets. Corresponding letters in the several figures of the drawings designate like parts.

50 The beam A has secured against its bottom the axle, upon the ends of which are journaled the hubs of truck-wheels B B', that have broad rims, and are intended to pass over the furrows after the corn is dropped therein, and to close the same, and one of these wheels, B, has secured to its hub a sprocket-wheel, a.

55 Upon the axle-beam A are secured two longitudinal beams, C C, which at their rear ends are connected by a cross-beam, D, and upon the front ends of beams C C is rigidly secured a cross-beam, E, the ends of which project beyond beams C C.

60 To the under side of beam E are secured two hanger-bearings, b, that carry shaft F, and upon this shaft F is loosely sleeved a sprocket-wheel, G, which, by an endless chain, H, is 65 driven from sprocket-wheel a of traction-wheel B. This sprocket-wheel G has a projecting rim to one side, the inner surface of which is turned to be true, concentric with the bore of the hub of such wheel. Inside of the rim of 70 wheel G is rigidly mounted upon shaft F a hub, R, that has two diametrically-opposite arms. To the end of each such arm is pivotally secured by a screw, e, a pawl, d, that has an eccentrically-faced end, which is turned against 75 the interior surface of the rim of sprocket-wheel G by a spiral spring, e, and has a curved arm that extends toward the center of wheel G, past shaft F, in such a manner that the arms of both pawls d are at opposite sides of such shaft. 80 A sleeve, f, that has a conical or spherical end, is bored to slide upon shaft F, and by a link, g, is coupled to the end of lever I, that is pivoted to the depending bracket h, secured to beam E. This sleeve, when pushed by lever I toward 85 hub R, will enter between the arms or pawls d, and will turn their eccentric faces away from the internal surface of the rim of sprocket-wheel G, so as not to come in contact therewith; but when shifted away from hub R it will release the pawls d, the eccentric faces of which 90 will then turn against the rim of sprocket-wheel G in a manner that the shaft F will be locked with such sprocket-wheel to rotate therewith while the machine is moving forward, but to slip and have no hold with a rearward motion of the same. Upon shaft F is 95 100

also rigidly mounted a disk, J, having a crank-pin, *s*. A pending bracket, K, is secured to beam E, the end hub of which forms a sleeve-bearing for shaft F, and has a rigid diametrical plate, *k*. Against each end of such rigid plate *k* is pivotally secured the end of a vibratable arm, *i* and *i'*, and these arms *i i'* are coupled together in their middle by a link, *j*, in a manner that they will vibrate simultaneously. The swinging ends of these arms will alternately be brought in contact with the rotating crank-pin *s* of disk J, that with pushing one arm, *i*, inward the other arm, *i'*, will be swung outward, and vice versa, in a manner to vibrate such arms alternately at uniform intervals. The arm *i* has a projecting stud, *l*, that engages with a notch of crank L, pivoted to a hub projecting from the forward end of bracket K in a manner that the alternate vibrations of arms *i i'* will transmit an intermittent oscillating movement to such crank L. This crank L, by suitable connections, is to be coupled with the slides of the seed-boxes, to open and close the same with each oscillation. To the ends of shaft F are coupled, by universal joints *m*, shafts M, which are supported in V-brackets *n*, that are secured to the ends of beam E. Upon the end of each shaft M is rigidly mounted the hub of a rectangular box, N, that forms the guide for two radial bars, O O', placed one against the other, and to slide longitudinally therein. Each bar O O' has a thickened end that forms a shoulder for limiting its movement, and also has secured a bracket, *o*, with a hook to its ends, one of which brackets, that is secured to bar O, projects through a slot in bar O', and both these brackets are coupled together by a spiral spring, *p*, that will push such bars O O' out to their limited full extent, and will allow either one to yield to an end-pressure. With this arrangement the arms O O' not only will accommodate themselves to the undulations of the ground, but with any more serious obstruction the shaft-extension M will yield also, so as to insure perfect safety of these parts against breakage. As the machine passes over the field the ends of arms O O' will make impressions in the ground, that will be the guide for the machine to plant the next adjacent rows of corn. In case the corn-marker arms O O' are not required, as with the last rows of corn to be planted, or while the machine is transported

to or from the field, they can be raised and locked in an elevated position by pin *q*, passed through a hole in V-bracket *n*. 55

The position of lever I is such that the driver can operate it from his seat, and thus can start and stop the rotation of shaft F, that operates the seed-box slides and carries the corn-plant markers. 60

The devices described and shown are simple in their construction and reliable in their operation.

I am aware that it is not new to employ in 65 corn-planters an axle divided into three parts the sections of which are connected by universal joints, the object being to allow the wheels to accommodate themselves to the inequalities of the surface; and I am also aware 70 that it is old to employ in such devices yielding rods to mark the ground, and therefore I do not claim those features, broadly.

What I claim is—

1. In a corn-planter, the sprocket-wheel G, 75 sleeved upon shaft F, and having a projecting rim, in combination with the two-armed hub R, rigidly mounted upon such shaft, and having eccentrically-faced pivotal pawls *d*, and springs *c*, and with conical sleeve *f*, coupled 80 with lever I, all substantially as described, to operate as specified.

2. In a corn-planter, the disk J, with crank-pin *s*, rigidly mounted upon shaft F, in combination with bracket K, vibratable arms *i i'*, 85 connected by link *j*, and with notched crank L, all substantially as and for the purpose described, to operate as specified.

3. In a corn-planter, and in combination with the shaft F, the auxiliary shafts M M', 90 and markers O O', said shafts M M' connected to shaft F by universal joints *m*, and supported in V-shaped brackets *n*, substantially as described and shown.

4. In a corn-planter, the combination, with 95 shafts F M M', connected by universal joints, as described, of springs *p*, brackets *o o*, and markers O O', the marker O' being slotted, as described, and for the purpose set forth.

In testimony whereof I affix my signature in 100 presence of two witnesses.

LOUIS HOLLAND LETZ.
